STATIONARY PISTON AIR COMPRESSOR

Orlando B. Johnson, Boise, Idaho

Application October 26, 1937, Serial No. 171,144

4 Claims. (Cl. 230—208)

This invention relates to air or gas compressors, and more particularly of the type wherein the pistons thereof remain stationary and the cylinders move thereover.

The primary object of the invention is to provide a compressor having means for cooling the interior of the pistons, during the compressing operation.

An important object of the invention is to provide a system of this character for compressing air or gas, including a main cylinder connected with an auxiliary cylinder of a smaller capacity than the first mentioned cylinder, the auxiliary cylinder receiving air from the main cylinder for multiple storage compression.

Another important object of the invention is to provide an air or gas compressor wherein the cylinder thereof swings on a horizontal pivot, as the connecting rod or link swings with the crank shaft, associated therewith, to the end that the connecting rod or link operates in a direct line with the center of the cylinder with an increase of power over compressor structures wherein the connecting rods operate at an oblique angle with respect to the wall of the cylinder.

Another object of the invention is the provision of filtering means, whereby the air or gas being compressed, may be freed of all foreign matter prior to the passage of the air or gas into the cylinder.

A still further object of the invention is the provision of means for distributing lubricating material over the wall of the cylinder, during the compressing operation.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a longitudinal sectional view through a compressor constructed in accordance with the invention.

Figure 2 is a longitudinal sectional view taken through the first stage compressor, the view being taken at right angles to Figure 1.

Figure 3 is a sectional view taken on line 3—3 of Figure 2.

Figure 4 is a longitudinal view through a pis-

ton of a modified form of the first stage compressor.

Figure 5 is a sectional view taken on line 5—5 of Figure 4.

Figure 6 is a sectional detail view illustrating 5 a modified form of valve wherein a rubber washer is used.

Figure 7 is an end elevational view of the valve.

Figure 8 is a longitudinal sectional view 10 through the second stage compressor.

Figure 9 is a sectional view taken on line 9—9 of Figure 8.

Figure 10 is a sectional view through a modified form of second stage compressor. 15

Figure 11 is a sectional view taken on line 11—11 of Figure 10.

Figure 12 is a view illustrating means for cooling the interior of the piston, by means of an air blast. 20

Referring to the drawings in detail, the compressor embodies a base comprising end bars 5 and 6 connected by means of the bars 7 arranged in parallel spaced relation with respect to each other. 25

Mounted on the bar 5, are bearings 8 in which the power shaft 9 operates, the power shaft being supplied with a pulley 10 that receives its motion through the belt 11 that in turn is operated by a suitable power device not shown. 30

As clearly shown by the drawings, the device embodies a main or first stage compressor indicated generally by the reference character 12, and an auxiliary or second staged compressor indicated by the reference character 13. The first stage compressor comprises a stationary piston indicated by the reference character 14, the piston 14 being supported on the stationary pipes 15 and 16 that are mounted in suitable supports secured to the bars 7, and connect with 40 the stationary piston 14 to deliver the cooling liquid, to the interior of the stationary piston. 35

Mounted within the stationary piston 14, is a manifold assembly embodying a central substantially wide manifold 17, and narrow manifolds 18, the manifolds 17 and 18 being connected by a series of pipes 19. These manifolds 17 and 18 are circular in construction, the peripheries of the manifolds being spaced from the wall of the stationary piston, as shown by Figure 1 of the 50 drawings. The pipe 20, which connects with the wide manifold 17, provides the exhaust pipe for the manifold. Connected with the pipe 20, is a flexible pipe or hose 21 that establishes communication between the manifold 17, and the interior 55

of the piston forming a part of the auxiliary or second stage compressor.

As clearly shown by Figure 1 of the drawings, pipes 22 communicate with the manifold 18, and extend through the ends of the piston 14, where they are supplied with valve seats 23, against which the valves 24 seat. These valves are seated, by means of the coiled springs 25, that normally urge the valves outwardly and are opened under air pressure entering the piston.

The first stage compressor also includes a movable cylinder 26 which is formed with elongated openings 27 providing clearances for the pipes 15 and 16. A yoke indicated by the reference character 28 is connected with one end of the cylinder 26, and includes a connecting link 29 that connects with the crank 30 of the power shaft 9. Thus it will be seen that due to this construction, the cylinder 26 is moved over the piston to accomplish the purpose of the invention.

The ends of the cylinder 26, are closed by means of the removable heads 30, each of which being provided with an opening providing a valve seat, for the valve 31 associated therewith.

Each valve 31 is provided with a valve stem 32 operating through a bracket 33, there being provided a coiled spring 34 on the valve stem, for normally urging the valve to its closed position.

Each cylinder head also includes a housing 35 which has its outer end closed by means of the filtering member 36, so that air or gas drawn into the cylinder, will be thoroughly filtered.

The auxiliary second stage compressor embodies a stationary piston 37 formed with an opening into which one end of the pipe 38 extends, the pipe 38 being connected with the pipe 16 by means of the coupling 39. Connected with the piston, and disposed directly opposite to the pipe 38, is a pipe 40 through which the cooling liquid passes after it has passed through the pistons, cooling the pistons, during the compressing operation. The flexible pipe or hose 21 connects with the pipe 41 that extends through the piston 37 longitudinally thereof, the ends of the pipe 41 being formed into valve housings 42 in which the valves 43 are positioned, the valves 43 opening outwardly, so that air entering the pipe 41, may pass into the spaces between the ends of the cylinder 44 and the ends of the piston 37. The pipe 45 which also extends longitudinally of the piston, is provided with valve housings 46 at its ends in which the valves 47 operate, the valves 47 opening inwardly against the tension of the springs 48, when air or gas compressed, forces the valves open. An outlet pipe indicated by the reference character 49 connects with the pipe 45. The ends of the piston 37, are provided with passageways, the outer walls of which being perforated, to allow lubricating oil entering the passageways to flow onto the wall of the cylinder 44, lubricating the cylinder. A pipe indicated by the reference character 50, connects with the pipe 51, which in turn is in communication with the passageways formed in the ends of the piston, through which lubricating oil finds its way to the passageways.

The reference character 52 designates a pipe that extends longitudinally of the piston, and establishes communication between the passageways at the ends of the piston, so that oil may pass from the passageways into the pipe 52. A pipe indicated by the reference character 53 connects with the pipe 52, permitting the oil to pass from the pipe 52.

Connected with the cylinder of the second

stage compressor, is a yoke 54 that includes the connecting rod 55 that connects with the crank 56 of the power shaft 9, so that as the power shaft rotates, reciprocatory movement will be imparted to the cylinder, moving the cylinder 5 over the piston 37.

In the modified form of main compressor or first stage compressor, as shown by Figure 4 of the drawings, the reference character 57 designates the stationary piston, which is hollow 10 and supplied with pipes 58 arranged in pairs as shown by Figure 5 of the drawings, the pipes extending throughout the entire length of the piston 57. These pipes 58 are formed with enlargements 59 at their ends providing housings 15 for the valves 60, which are held to their seats by means of the springs 61. These pipes 58 are in communication with the pipe 62 through which air passes to a pipe not shown, and which leads to the auxiliary or second stage compressor as 20 associated therewith. In this form of the invention, the piston shown by Figure 4 of the drawings, is substituted for the piston shown in Figure 2 of the drawings.

In the modified form of the auxiliary compressor or second stage compressor, as shown by Figure 10 of the drawings, the piston is indicated by the reference character 63, the piston being hollow to support the manifold assemblies 25 each of which includes a central manifold 64 30 and end manifolds 65, the manifolds 64 and 65 being connected by a series of pipes 66, as shown by Figure 10. Pipes 67 connect the manifolds 65 with the ends of the piston, and provide housings for the valves 68 which are forced to their 35 seats by means of the springs 69.

The valves 70, which are supported within the pipes 67 that connect certain of the manifolds 65 with the ends of the pistons, open outwardly, against the action of the coiled springs 71. Thus it will be seen that air drawn into the manifolds at one side of the piston, will be forced outwardly into the spaces between the ends of the piston and cylinder operating over the piston, through the valves 70. The pipe 72 extends 40 into the central manifold of one section 45 and communicates with the inner pipe of the main compressor or first stage compressor.

It may be desirable to use valves such as shown by Figure 6 of the drawings, in lieu of the valves of the spring pressed type, shown in Figures 1 and 2 of the drawings. The valve in this form of the invention is indicated by the reference character 73 and is of the flap or rubber washer type that normally closes the opening 74 in one 50 end of the pipe 75, with the result that pressure against the washer in one direction, will cause the washer to move away from the openings 74, allowing air to enter. As the pressure is relieved, the washer will seat, closing the openings 55 of the valve.

As shown by Figure 12 of the drawings, the cooling medium is in the form of air, which is blown into the piston, by means of the fan 76 which is mounted in one end of the pipe 77 60 which has one end thereof extended through an opening in the piston.

It might be further stated, that in the preferred form of the invention, the cooling medium is liquid, which is pumped through the 70 pipe 15, by means of the pump 78 operated by power supplied to the pump, through the medium of the belt 79.

In the operation of the device, the main or first stage compressor, as well as the auxiliary 75

or second stage compressor, are operated by moving the cylinders over the pistons, the movement of the cylinders resulting in air entering the manifold assemblies of the pistons, from where 5 the compressed air will be forced to a suitable tank.

During the compressing operation, the pump 18 forces cooling liquid through the pipe 15, from where it passes around the various pipes connecting the manifolds of the manifold assembly. The water then passes through the pipes 16 and 38, entering the hollow piston of the auxiliary or second stage compressor, cooling the piston. The cooling liquid is now passed or exhausted through 15 the pipe 40. From the foregoing it will be seen that due to the construction shown and described, the manifold assemblies which include the pipes and manifolds connected by the pipes, are maintained cool at all times, during the compressing 20 operation.

From the foregoing it will be seen that due to the construction of the device, the cylinder and piston will swing with the connecting rod, with the result that the connecting rod operates 25 in a direct line with the center of the cylinder at all times.

Having thus described the invention, what is claimed is:

1. An air compressor comprising a main compressor, a substantially small auxiliary compressor adapted to receive compressed air from the main compressor, each compressor including a stationary piston and a cylinder operating over the piston, pipes within the pistons, said pipes 30 communicating with the space between the piston heads and ends of the cylinders and through which compressed air passes, means for directing cooling liquid into the pistons to circulate around the pipes, cooling the pipes, a pipe establishing communication between the spaces within the 35 pistons between the pipes and the walls of the pistons whereby cooling liquid passes from one

piston to the other, and connecting rods connected with the cylinders by means of which the cylinders may be operated.

2. An air compressor comprising a stationary piston, a manifold assembly within the piston, 5 said manifold assembly comprising circular drum-like end members and a central drum-like member, pipes establishing communication between the central drum-like member and drum-like end members, valves controlling the passage 10 of air into the manifold assembly with each stroke of the cylinder, an inlet pipe establishing communication between the space around the manifold assembly and source of cooling liquid supply, and a pipe for exhausting the cooling 15 liquid from the space.

3. An air compressor comprising a stationary piston, a cylinder movable over the piston, a manifold in the piston, said manifold including drum-like end members, a central enlarged drum-like member, pipes establishing communication between the drum-like members, valves in the ends of the pistons, said valves controlling the passage of air into the manifold, a pipe for delivering cooling liquid to the interior of the 25 piston for circulation around the manifold, and a pipe for exhausting cooling liquid from the piston.

4. An air compressor comprising a stationary piston, a cylinder operating over the stationary 30 piston, a manifold within the piston, said manifold comprising end members and a central member, a plurality of pipes connecting said end members and central member establishing communication therebetween, pipes connected with the 35 end members and extending through the ends of the piston, valves in the outer ends of the latter pipes for controlling the passage of air into the manifold, and means for circulating cooling liquid through the pistons exteriorly of the manifold. 40

ORLANDO B. JOHNSON.
